UNITED STATES PATENT OFFICE.

JOHN C. RISLING, OF CHICAGO, ILLINOIS.

WATER-HEATING DEVICE.

1,074,741.

Specification of Letters Patent.

Patented Oct. 7, 1913.

Application filed April 24, 1913. Serial No. 763,344.

To all whom it may concern:

Be it known that I, JOHN C. RISLING, a citizen of the United States, and a resident of the city of Chicago, county of Cook, and State of Illinois, have invented certain new and useful Improvements in Water-Heating Devices, of which the following is a specification.

My invention relates to improvements in water heating devices and more specifically to improvements in that type thereof used in kitchens and commonly known as domestic boilers.

The object of my invention is the production of a boiler of the character mentioned which will be equipped with heating apparatus whereby the water may be instantaneously heated notwithstanding the fact that the stove or furnace with which the boiler is connected in order to effect the heating of the water thereof, is not in use.

A further object is the production of a water heating device, as mentioned, which will be of durable and economical construction and efficient in use.

Other objects will appear hereinafter.

With these objects in view my invention consists in the combinations and arrangements of parts hereinafter described and claimed.

The invention will be best understood by reference to the accompanying drawings forming a part of this specification, and in which,

Figure 1 is a central vertical section of a water heating device embodying my invention, Fig. 2 is a horizontal section taken on line $x-x$ of Fig. 1, Fig. 3 is a top plan view of the burner of the construction, and Fig. 4 is a partially sectional side elevation of another form of my heating device.

The form of construction as illustrated in Fig. 1 of the drawings comprises a base 1 upon which is supported a vertically extending cylindrical housing 2. Mounted upon the upper end of the housing 2 is the boiler or water container 3. Extending into the interior of the member 3 from the upper end wall thereof is the water inlet pipe 4, with which communicates the water supply pipe 4'. Depending from the bottom of the boiler 3 is a pipe 5 which communicates with the lower end of a hollow circular member 6 positioned as shown within the housing 2. Extending through the interior of the member 6 is a plurality of vertically extending

flues 7. The upper end of the member 6 communicates through a pipe 8 with a comparatively thin flat circular hollow member 9, the member 9 being so arranged that gas passing through the flues 7 will impinge upon the under side thereof. Leading upwardly from the upper wall of the member 9 is a pipe 10 which passes axially through a flue 11 formed centrally through the interior of the boiler 3. A branch 12 leads from the upper end of the pipe 10 to return water passing through the pipe 10 to the boiler 3 in the event of the same not being drawn from the outer end of the pipe 10 which, when the device is in use, will be connected with a service faucet.

Mounted in the lower end of the housing 2 is a burner 13 so arranged that the flame jets issuing therefrom, during the use of the device, will impinge upon the under side of the member 6. In using the device then, it will be seen, that the heated gases after impinging upon the bottom of the member 6 will pass around the periphery thereof or through the flues 7 in the rise of said gases, the members 6 and 9 being of a diameter less than that of the interior of the housing 2 in order to permit of the passage of the gases around the peripheries 80 thereof in the manner mentioned with regard to the member 6. The gases passing through the flues 7 will impinge upon the under side of the member 9 and thence will pass around the periphery thereof and impinge upon the bottom of the boiler 3, being finally exhausted after passage through the flue 11 from the upper end of the latter. With the arrangement set forth, it will be seen that, an effectual arrangement is employed for utilizing the heated gases issuing from the burner 13 to the fullest extent, a maximum surface for contact of the heated gases with walls through which the heat will be conducted and utilized to heat the water 100 passing through the device being presented. With this system the water will, of course, descend through the pipe 5 into the member 6, whence the same, after heating, will automatically rise through the pipe 8 and into the member 9 and thence into the pipe 10.

By reason of the arrangement employed whereby a maximum extent of surface for contact with the heated gases in the heating of the water is afforded, the water in passing from the boiler through the pipe 5 and thence through the various pipes and the

members until the same reaches the upper end of the pipe 10, will be instantaneously heated as desired.

In Fig. 4 is shown a form slightly modified. In this form the heating apparatus is arranged independent of the boiler, alongside the same. The heating apparatus here used is, however, of the same construction as described as is also the boiler 3 although the latter, with this arrangement may be made longer or of greater capacity. In this form the boiler 3 is supported as shown upon the base 1, the housing 2 being supported upon its own base 2'. A valved drain 14 leads from the bottom of the member 6, as shown, so as to permit of the draining of the apparatus when desired in the cleansing thereof.

While I have illustrated and described the preferred forms of construction for carrying my invention into effect, these are capable of variation and modification without departing from the spirit of the invention. I, therefore, do not wish to be limited to the precise details of constructions set forth, but desire to avail myself of such variations and modifications as come within the scope of the appended claims.

Having described my invention what I claim as new and desire to secure by Letters Patent is:

1. In a water heating device, the combination of a boiler; heating apparatus, said heating apparatus comprising a vertically extending housing open at its respective ends; a burner arranged in said housing; a comparatively high hollow member arranged above said burner; a communication between said member and said boiler; a plurality of elongated vertically extending flues traversing the interior of said member; a second hollow member arranged above said

first mentioned member so that gas passing through said flues will impinge upon the under side of said second mentioned member; a central communication between said first and second mentioned members; a pipe leading from said second mentioned member; and a flue leading from the upper end of said housing surrounding said last mentioned pipe, substantially as described. 45 50

2. In a water heating device, the combination of a boiler; heating apparatus comprising a vertically extending housing open at its respective ends; a burner arranged in said housing at the lower end thereof; a comparatively high hollow member arranged above said burner; a communication between the lower end of said member and the lower end of said boiler; a plurality of 55 60 elongated vertically extending flues traversing the interior of said member; a second hollow comparatively thin flat member arranged above said first mentioned member so that gas passing through said flues will 65 impinge upon the under side of said second mentioned member; a central communication between the upper end of said first mentioned member and the lower end of said second mentioned member; a pipe leading from the upper end of said second mentioned member having a branch returning to 70 75 said boiler; and a flue leading from the upper end of said housing surrounding the said last mentioned pipe, substantially as described.

In testimony whereof I have signed my name to this specification in the presence of two subscribing witnesses.

JOHN C. RISSLING.
